US00D810156S

(12) **United States Design Patent** (10) **Patent No.:** **US D810,156 S**
Lin (45) **Date of Patent:** **** Feb. 13, 2018**

(54) **3D PRINTER**

(71) Applicants: **XYZPRINTING, INC.**, New Taipei (TW); **KINPO ELECTRONICS, INC.**, New Taipei (TW)

(72) Inventor: **Yu-Hao Lin**, New Taipei (TW)

(73) Assignees: **XYZPRINTING, INC.**, New Taipei (TW); **KINPO ELECTRONICS, INC.**, New Taipei (TW)

(**) Term: **15 Years**

(21) Appl. No.: **29/586,273**

(22) Filed: **Dec. 1, 2016**

(51) **LOC (11) Cl.** **15-09**

(52) **U.S. Cl.**

USPC **D15/135**; D15/122; D18/50

(58) **Field of Classification Search**

USPC D7/323, 331, 363, 665, 668; D8/499; D14/420-425; D15/122, 135, 138, 145, D15/146; D18/4, 6, 7, 14, 19, 36, 37, 38, D18/39, 50, 53, 54, 54.1, 55, 59; D19/67, 100, 108; D24/232

CPC . B29C 67/00; B29C 67/0051; B29C 67/0055; B29C 67/0059

(57) **CLAIM**

The ornamental design for a 3D printer, as shown and described.

DESCRIPTION

FIG. 1 is a perspective view of a 3D printer showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is second perspective view thereof; and,

FIG. 9 is third perspective view showing the 3D printer. The broken lines show portions of the 3D printer that form no part of the claimed design.

1 Claim, 9 Drawing Sheets
